UNITED STATES PATENT OFFICE.

JAMES DODGE, OF NEWARK, NEW JERSEY.

VISE.

SPECIFICATION forming part of Letters Patent No. 711,948, dated October 28, 1902.

Application filed June 13, 1902. Serial No. 111,469. (No model.)

To all whom it may concern:

Be it known that I, JAMES DODGE, a citizen of the United States, residing at Newark, in the county of Essex and State of New Jersey, 5 have invented certain new and useful Improvements in Vises; and I do hereby declare the following to be a full, clear, and exact description of the invention, such as will enable others skilled in the art to which it applies to make and use the same, reference being had to the accompanying drawings, and to numerals of reference marked thereon, which form a part of this specification.

My present invention relates to improvements in vises; and the invention has reference more particularly to a novel construction of vise comprising a pair of adjustable sliding jaws for bringing said jaws in their approximate holding relation with the piece 20 of work which is to be held between the jaws and provided with a tightening means cooperating with one of the jaws of the vise for causing the positive holding engagement of the said jaws of the vise with the work held between the said jaws.

The present invention therefore has for its principal objects to provide a simple, inexpensive, and efficient construction of vise both jaws of which are adjustable with relation to the main stock or bar, the several 30 parts being slidably arranged, thereby doing away with the usual screw shank or stock now or ordinarily used and providing a vise which may be used with economy of time and 35 a saving of labor in doing a variety of work where a vise is serviceable.

The invention consists, primarily, in the novel construction of vise hereinafter more fully set forth, as well as in the various novel 40 arrangements and combinations of the parts thereof, all of which will be more particularly described in the following specification and then finally embodied in the clauses of the claim.

45 The invention is clearly illustrated in the accompanying drawings, in which—

Figure 1 is a side elevation of a vise made according to the principles of my invention; and Fig. 2 is a longitudinal vertical section 50 of the same, the said view illustrating the holding-jaws of the vise in their relatively locked engagement on the main stock or bar

of the vise. Fig. 3 is a detail view, on an enlarged scale, of a portion of the main stock or bar and a part in section of one of the jaws 55 of the vise, the parts being represented in their unlocked relation to permit of a sliding movement of the jaw on said stock or bar; and Fig. 4 is a transverse vertical section on an enlarged scale, said section being taken 60 on line 4 4 in Fig. 2 looking in the direction of the arrow x. Fig. 5 is a perspective view of a holding or locking pin or key which is used with the said main stock or bar and one of the said holding-jaws. Fig. 6 is a side 65 elevation of a modified construction of vise, but still embodying the leading features of my invention. Fig. 7 is a top or plan view of the same; and Fig. 8 is a transverse vertical section taken on line 8 8 in Fig. 6 looking in the direction of the arrow y in said similar figure.

Similar characters of reference are employed in all of the said hereinabove-described views to indicate corresponding parts. 75

Referring now to the several figures of the drawings, the reference character 1 indicates the complete construction of vise, of which the main stock or bar is indicated by the reference-numeral 2, and 3 and 4 are the respective jaw-bodies. The said jaw-body 3 in Figs. 1 to 4, inclusive, is made with the usual jaw portion or member 5 and with a downwardly-extending leg or fastening member 6, which is suitably secured at the front edge of the 80 work-bench 7 by means of bolts 8 or any other suitable fastening means. The said jaw-body 3 is provided in its main body portion with a rearwardly-extending opening 9, preferably of a rectangular cross-section, in which is fitted and is slidably arranged, so as to be capable of being pulled in or out, the main portion of said stock or bar 2. This stock or bar 2 is of a similar cross-section, as clearly represented in Fig. 4 of the drawings; but of 85 course it will be evident that the said opening 9 and said stock or bar 2 may be of any other cross-section. The said jaw 3 is also provided with transverse or laterally-extending ducts 10 and 11 of a circular cross-section 90 and the semicircular duct portion 12, arranged directly above and in communication with the said main opening 9, the said ducts 10 and 11 and the semicircular duct portion 12 all

being in alinement and adapted to receive for rotative arrangement therein a holding-pin 13. The said pin 13 is provided with a suitable finger-piece 14 or other suitable means 5 for turning the said pin and is retained in place by a washer 15 and a small pin 16, connected with the end portion 17 of the pin 13, as illustrated; but it will be understood that any other fastening or retaining means may 10 be employed with the said pin 13 for holding it in its operative and rotative position in said ducts 10 and 11 and the duct portion 12. The said holding-pin 13 is also made with a cut-away portion 18, having a flat surface 19 directly beneath the upper semicylindrical and central portion 20 of said pin 13, substantially as illustrated. When this upper semicylindrical portion 20 of the said pin 13 has been arranged in the semicircular duct 12 of the 15 jaw-body 3, then an unobstructed passageway for the sliding movement of the stock or bar 2 is provided within the said main body portion of said jaw 3, as will be clearly evident from an inspection of Figs. 2 and 4; but 20 when said pin 13 has been rotated in said ducts 10 and 11, so as to bring its semicylindrical portion 20 out of the semicircular duct portion 12 and into one of a number of semi-circular and laterally-extending grooves 21 in 25 the upper edge portion of the stock or bar 2, then the said stock or bar will be retained in a held or fixed position in the opening 9 of the jaw-body 3, as illustrated in Fig. 3, until the said pin 13 is again rotated a one-half turn, 30 whereby the semicylindrical portion 20 again enters the semicircular duct portion 12 to permit of a sliding movement of the stock or bar 2 and bring the latter into any other adjusted relation with the jaw-body 3. The forward end portion of the said stock or bar 2 is 35 made with a screw shank or member 22, the part 23 of said stock or bar 2, from which the said screw shank or member 22 extends, being suitably arranged in a receiving-socket 40 24, formed on the inner side of the other jaw-body 4 of the vise, as shown. The said jaw-body 4 is provided with the usual jaw portion 25, and in the wall 26 of said jaw-body 4 there is an opening 27, through which the 45 said screw shank or member 22 extends. The arrangement of the said part 23 and the screw shank or member 22 of the said stock or bar 2 within the socket 24 and the opening 27, respectively, is such that the jaw-body 4 is capable of a limited movement, substantially as and for the purposes to be hereinafter more particularly set forth. Upon the said screw shank or member 22 is operatively arranged a nut 28, having a reduced portion 50 29, on which is placed a wrench 30, which can be placed about the polygonal portion 31 of the nut 28 for turning the latter, and thereby bringing the preferably conically formed end surface 32 in operative contact with a cone-shaped receiving depression 33 in the jaw-body 4 and forcing the latter in a direction 55 toward the other jaw-body 3, as will be

clearly evident. The jaw-body 3 is also preferably made with the inclined surface 34 for clearance.

Now suppose it is desired to hold and secure a piece of work between the two holding-jaws of the two jaw-bodies 3 and 4. The pin 13 is turned so as to stand in the position indicated in Figs. 2 and 4, and the stock or bar 2 and jaw-body 4 are then both pulled forward in the direction of the arrow x, so as to separate the holding-jaw portions of the two jaw-bodies 3 and 4 the required distance to receive the piece of work. The pin 13 is then given a half-turn to bring the semicylindrical part 18 in the groove 21 of the stock or bar 2, which has been brought directly below the semicircular duct portion 12 in the opening 9. The work is now held by hand between the jaw portions of the jaw-bodies 3 and 4, and the nut 28 is firmly screwed against the outer face of the jaw-body, whereby said jaw-body 4 will be moved toward the work and the latter will be firmly and securely held in a fixed position between the jaw portions of the two jaw-bodies 3 and 4.

In Figs. 6, 7, and 8 of the drawings I have illustrated the use of my novel construction of vise with a table or bench, the stock or bar 2 in this case being arranged in a fixed position upon and extending across the top of the table or bench, but in this instance both jaw-bodies 3 and 4 being slidably arranged on said stock or bar 2, whereby the vise is especially adapted for the holding between the jaw portions of the vise of pieces of work of great widths. In this construction of vise the stock 2 and the jaw-bodies 3 and 4 are made in the same manner as the corresponding parts of the vise construction described and illustrated in connection with Figs. 1 to 4, inclusive. In the present construction, however, the stock or bar 2 is provided with a screw-threaded shank 35 at its rear end, 100 which is suitably secured by means of a nut 36 or other suitable fastening means to a standard or bracket 37, extending in an upward direction above the upper surface of the table or bench, as shown. Suitably secured 105 to the front of the table or bench, by means of bolts 38, is a plate 39, having a rectangularly-formed opening 40, in which the said stock or bar is arranged, as clearly illustrated, and it will thus be seen that said stock or bar 110 2 is supported in a fixed position above the table or work-bench. The jaw-body 3 in this case, however, is made without the downwardly-extending leg or fastening member 6, said jaw-body 3 being slidably arranged upon 115 the stock or bar 2, which is provided with the grooves 21 and is locked or held in its adjusted position, by means of the pin 13, in the manner herein described in connection with the construction of vise illustrated in Figs. 1 120 to 4, inclusive. The other jaw-body 4 is tightened against the work, by means of the nut 28 and wrench 30, in the same manner as 125 has been hereinabove described.

I am fully aware that changes may be made in the various arrangements and combinations of the parts without departing from the scope of my present invention. Hence I do not limit my invention to the exact arrangements and combinations of the parts as described in the previous specification and as illustrated in the accompanying drawings, nor do I confine myself to the exact details of the construction of the said parts.

Having thus described my invention, what I claim is—

1. In a vise, the combination with a non-rotative stock, provided with transverse grooves, and a pair of jaw-bodies 3 and 4, the said jaw-body 3 having a longitudinally-extending opening in which the said stock is arranged, all arranged to be brought in sliding relation with one another, for adjustment according to the work to be held, the said jaw-body 3 being provided with a pair of laterally-extending ducts 10 and 11, and a semicircular duct 12, all in alinement, and a pin in said ducts, having a cut-away part and correspondingly-placed semicylindrical body portion adapted to register with one of said grooves in the stock to hold said jaw-body in its fixed relation to the said stock, and said pin being rotatively arranged so that said semicylindrical body portion can be removed from its holding engagement with the groove in the stock and made to register with said semicircular duct 12 to permit of a sliding movement, and means on the forward end portion of said stock for engagement with said jaw-body 4 to move said jaw-body 4 into its firm holding engagement with the work, substantially as and for the purposes set forth.

2. In a vise, the combination, with a non-rotative stock, provided with transverse grooves, and a pair of jaw-bodies, 3 and 4, the said jaw-body 3 having a longitudinally-extending opening in which the said stock is arranged, all arranged to be brought in sliding relation with one another, for adjustment according to the work to be held, the said jaw-body 3 being provided with a pair of laterally-extending ducts 10 and 11 and a semicircular duct 12, all in alinement, and a pin in said ducts having a cut-away part and correspondingly-placed semicylindrical body portion adapted to register with one of said grooves in the stock to hold said jaw-body in its fixed relation to the said stock, said pin

being rotatively arranged so that said semicylindrical body portion can be removed from its holding engagement with the groove in the stock and made to register with said semicircular duct 12 to permit of a sliding movement, and means on the forward end portion of said stock for engagement with said jaw-body 4 to move said jaw-body 4 into its firm holding engagement with the work, consisting, essentially, of a screw-shank on the said forward free end portion of the stock, and a nut on said screw-shank adapted to be screwed against the said jaw-body 4, substantially as and for the purposes set forth.

3. In a vise, the combination with a non-rotative stock, provided with transverse grooves, and a pair of jaw-bodies 3 and 4, the said jaw-body 3 having a longitudinally-extending opening in which the said stock is arranged, all arranged to be brought in sliding relation with one another, for adjustment according to the work to be held, the said jaw-body 3 being provided with a pair of laterally-extending ducts 10 and 11 and a semicircular duct 12, all in alinement, and a pin in said ducts, a cut-away part and correspondingly-placed semicylindrical body portion adapted to register with one of said grooves in the stock to hold said jaw-body in its fixed relation to the said stock, said pin being rotatively arranged so that said semicylindrical body portion can be removed from its holding engagement with the groove in the stock and made to register with said semicircular duct 12 to permit of a sliding movement, and means on the forward end portion of said stock for engagement with said jaw-body 4 to move said jaw-body 4 into its firm holding engagement with the work, consisting, essentially, of a screw-shank on the said forward free end portion of the stock, and a nut on said screw-shank adapted to be screwed against the said jaw-body 4, the said jaw-body 4 having a cone-shaped depression 33, and said nut having a cone-surface 32 for engagement with said depression substantially as and for the purposes set forth.

In testimony that I claim the invention set forth above I have hereunto set my hand this 10th day of June, 1902.

JAMES DODGE.
